Primary Examiner — Barbara Fox*Assistant Examiner* — Mehri F Bajoul(74) *Attorney, Agent, or Firm* — Ohlandt, Greeley, Ruggiero & Perle, L.L.P.(57) **CLAIM**

It is claimed the ornamental design for a packaging for oral appliance with container, as shown and described.

DESCRIPTION

FIG. 1 is a front left side perspective view of a packaging for oral appliance with container showing my new design; FIG. 2 is a front elevation view thereof; FIG. 3 is a left elevation view thereof; FIG. 4 is a right elevation view thereof; FIG. 5 is a top plan view thereof; FIG. 6 is a bottom plan view thereof; FIG. 7 is a front left perspective view thereof shown partially open; FIG. 8 is a front right perspective view thereof shown fully open; FIG. 9 is a rear left perspective view thereof shown fully open; and, FIG. 10 is a rear elevation view of the design shown in FIGS. 1-6.

The broken lines in the figures are for the purpose of illustration and form no part of the claimed design.

1 Claim, 8 Drawing Sheets(56)
